UNITED STATES PATENT OFFICE

MAGNUS RUDOLF KRAUL, OF PORTLAND, OREGON; ANNA E. KRAUL, ADMINISTRATRIX OF SAID MAGNUS R. KRAUL, DECEASED

RETORT FOR DISTILLING OIL SHALE AND THE LIKE

Application filed June 20, 1927. Serial No. 200,074.

My invention relates to vertical retorts adapted to destructive distillation of the hydro-carbons of various hydro-carbon bearing substances, and my invention especially relates to the destructive distillation and extraction of "crude oil" from oil shales.

The object of my invention is to provide simple means for arranging the material to be retorted in the form of a relatively thin vertical sheet composed of layers or small portions superimposed one upon the other, so that the layers or portions of the material will become quickly heated to the required temperature.

15 A further object of my invention is to provide a retort comprising a vertical rectangular elongate enclosure consisting of walls on two sides and one end, and divided on the interior by longitudinal spaced walls into a 20 distilling chamber, and a heating chamber on each side of the distilling chamber, with heating means located in each of said heating chambers, so that both sides of the sheet of material will be simultaneously and constantly exposed to the heat; and, further to 25 provide within and adjacent each of the longitudinal side walls of the distilling chamber a series of vertically spaced horizontal shelves, extending inward and sloping downward, and arranged in staggered relationship 30 with each other, whereby to hold small portions or layers of the material to be retorted, and feed the same from an upper shelf onto a lower. By such construction a relatively 35 thin sheet of the shale passes constantly through my retort and has both sides of the sheet subjected to the generated heat in the distilling chamber, so that the temperature of the shale may be quickly raised to the temperature required, and the reaction of the 40 shale to the heating will be continuous and rapid.

A further object of my invention is to provide for the ready removal, repair and replacement of the said shelves as may become necessary in service; and to that end I employ a removable frame within the distilling chamber which frame carries the said series of vertically spaced horizontal shelves, the spaces 45 under the shelves functioning as gas collect-

ing sheds and passageways, which open into said gas collecting chamber.

Further features of my invention, the details of construction of my retort and the mode of operation thereof are hereinafter 55 fully described with reference to the accompanying drawings, in which;

Fig. 1 shows a transverse central vertical section, taken on the line 1—1 of Fig. 3, and illustrates my retort comprising two units; 60

Fig. 2 shows a perspective view of the removable frame, supporting the material holding shelves;

Fig. 3 shows a central vertical section taken through one of the distilling chambers in 65 Fig. 1, and illustrates the details of construction;

Fig. 4 shows a horizontal section taken on the line 4—4 of Fig. 1, and illustrates further details of construction; 70

Fig. 5 shows an end elevation of my retort of two units.

My retort is preferably constructed to consist of a number of units, a retort of two units being shown in the drawings supported on a foundation *a* and enclosed at the sides by walls *b* and at one end by a wall *i*, all preferably of brick.

The distilling chambers *c* are formed by spaced walls *d* of steel plates also spaced from the walls of the retort, by which heating chambers *e* are also formed the latter chambers being closed by end walls *d'*, see Figs. 1 and 4.

Within each distilling chamber *c*, I provide 85 a removable elongate frame *g*, Fig. 2, both of the side walls of which are provided on the interior with a series of vertically spaced horizontal shelves *h*, sloping downwardly at an angle of approximately 45 degrees, the 90 shelves carried by the sides of the frame *g*, respectively are arranged in staggered relationship, said shelves being adapted to carry a relatively thin layer of shale each with the upper shelves discharging on the lower. 95

One end of the retort is also closed by a brick wall *i*, see Fig. 4, and the frame *g* will be inserted into the distilling chamber *c* and spaced from the said wall by flanges *g'*, see Fig. 3, thus forming a gas chamber *j*. The 100

end of the frame adjacent the gas chamber *j* is closed by a plate *g*², see Figs. 3 and 4, in which outlets *k* are provided at the end of the shelves *h* through which outlets the distilled gases from the shale collecting under the shelves *h* may pass into the gas chamber *j*.

The other ends of the distilling chambers are closed by removable plates *l*, see Figs. 3, 4 and 5, bolted to the end walls *d'* of the heating chamber *e* and by this construction the frame *g* may be easily removed for repairs to the shelves *h*, if required.

At the top of each distilling chamber, I provide hoppers *m*, the hoppers being connected to each other and discharging into the said distilling chamber, respectively, and a stack 2 from the heating chamber is arranged between the two hoppers and is connected to an outlet 3. By this arrangement waste gases from the heating chambers serve to pre-heat the shale in the hoppers before the shale is admitted into the distilling chamber.

The heating chambers located on the outer sides of the distilling chambers are provided with outlets 4 for the products of combustion.

A rotatable gate *n* is provided at the bottom of the hopper *m*, through which the admission of the shale into the distilling chamber is controlled.

A rotatable grate *o* is provided at the bottom of the distilling chamber, and both the gate *n* and grate *o* are connected by chains *p* and sprockets *q* so that they may be operated in unison to discharge the spent shale as fresh oil shale is admitted at the top.

A conveyor belt *r* is arranged below each of the distilling chambers to carry off the spent shale to another conveyor belt *s* outside the retort by which the spent shale may be conveyed to the "dump" or cars.

I provide ducts 5 leading through the end wall *i* from the gas chambers *j* to pipes 6 which may be connected to atmospheric condensers.

In the operation of my retort the distilling chambers will be charged with oil shale crushed to pieces of about one inch in size, and the retort will be heated until a temperature of approximately 800 degrees F. has been reached.

A very narrow distilling chamber and by providing the said inwardly and downwardly extending shelves *h* therein, I am enabled to treat a very narrow sheet of oil shale, since the said shelves provide increased heating surface in relation to the volume of shale to be treated, and the entire section of ore is thus quickly raised to the required temperature at which the hydrocarbons are separated from the oil shale in gaseous form and will pass under the shelves *h* through the vents *k* and thence into the gas chamber, and from there through the pipes 5 and 6 to an atmospheric condenser, since the gate *n* and the grate *o* also serve to seal the retort at the top and bot-

tom and prevent any of the gaseous hydrocarbons from escaping through the hoppers or from the bottom of the distilling chambers.

The thin sheet of oil shale contained in the distilling chambers will not pack at the bottom by its own weight, but will be supported more or less by the downwardly sloping shelves when at rest, at the same time will readily move downward over the shelves when the spent shale is being taken from the bottom of the distilling chamber.

The oil shale generally commences to give off the hydrocarbons somewhat before the temperature of 800 degrees F. is reached and by the time the oil shale has been subjected to this degree of heat for about forty minutes, since it has been preheated in the hoppers *m* which shorten the time required for raising the oil shales to this temperature, all the hydro-carbons will have been distilled and the gate *n* and grate *o* which are adapted to operate in unison will be operated to admit oil shale into the distilling chamber and discharge the spent shale from the bottom of the distilling chambers at such a rate that it will require approximately this period of forty minutes to pass through it.

Along with the hydrocarbons comprising the crude oil, other incondensable gases of hydro-carbon compounds are given off which I have found to be economically useful as fuel for the gas burners 10, as these incondensable gases have a low burning point, high heat value, and burn with little waste.

Another by-product, ammonium sulphate, is commonly obtained from oil shales, and with my retort I economically produce ammonium sulphate in quantity and quality equal to any other retorts within my knowledge, which I may separate in atmospheric condensers easily, since, I do not use super-heated steam, as the agent of distillation, which tends to complicate the recovery.

I claim:

1. In a retort, the combination of a vertical rectangular enclosure comprising walls on two sides and one end, longitudinal walls within the said enclosure arranged to divide the same into a central elongate distilling chamber and a heating chamber on each side of the distilling chamber, heating means located in each heating chamber, wall sections closing the other ends of said heating chambers, and removable wall plates secured to said wall sections closing the same end of the distilling chamber, a rectangular elongate frame in said distilling chamber, said frame comprising two opposite spaced sides each supporting a series of vertically spaced horizontal shelves extending inward midway of the distilling chamber and sloping downward, with the shelves of one series arranged in staggered relationship with those of the other, whereby to hold layers of the material being retorted, and to feed the same from

- an upper shelf onto a lower, said frame being of lesser length horizontally than the distilling chamber thereby to provide a gas-collecting chamber, at one end within the latter, spaces under the shelves adapted to constitute gas-collecting sheds, and passageways and which open into said gas-collecting chamber, said latter chamber adapted to be connected to gas withdrawing means.
2. In a retort, the combination of, a vertical rectangular enclosure comprising walls on two sides and one end, longitudinal walls within the said enclosure arranged to divide the same into an elongate central distilling chamber and a heating chamber on each side of the distilling chamber, heating means located in each heating chamber, wall sections closing the other ends of said heating chambers, and removable wall plates secured to said wall sections closing the same end of the distilling chamber, a rectangular elongate removable frame in said distilling chamber, said frame comprising two opposite spaced sides each supporting a series of vertically spaced horizontal shelves extending inward midway of the distilling chamber and sloping downward, with the shelves of one series arranged in staggered relation with those of the other, whereby to hold layers of the material being retorted and to feed the same from an upper shelf onto a lower, a gas-collecting chamber provided at one end of the distilling chamber, spaces under the said shelves constituting gas-collecting sheds and passageways which open into said gas-collecting chamber, said latter chamber adapted to be connected to gas withdrawing means.
3. In a retort, the combination of a vertical rectangular inclosure, the interior of the inclosure subdivided into plural distilling units, each composed of longitudinal spaced walls enclosing a central distilling chamber and a heating chamber on each side of the distilling chamber, heating means located in said heating chambers, the interior of the distilling chamber provided with a frame comprising two opposite spaced sides each side supporting a series of vertically spaced horizontal shelves extending inward midway of the distilling chamber and sloping downward with the shelves of one series arranged in staggered relation with those of the other, whereby to hold layers of the material being retorted and feed the same from an upper shelf onto a lower, a gas-collecting chamber provided at one end of the distilling chambers respectively, spaces under the said shelves adapted to constitute gas-collecting sheds and passageways which open into said gas collecting chambers, said latter chamber adapted to be connected to gas withdrawing means.
4. In a retort, the combination of, a vertical rectangular narrow distilling chamber, means for heating the two opposite sides thereof, the interior distilling chamber provided with a frame comprising two opposite spaced sides each side supporting a series of vertically spaced horizontal shelves extending inward midway of the distilling chamber and sloping downward, with the shelves of one series arranged in staggered relation with those of the other, whereby to hold layers of the material being retorted and to feed the same from an upper shelf onto a lower, a gas-collecting chamber provided at one end of the distilling chamber, spaces under the said shelves constituting gas-collecting sheds and passageways which open into said gas-collecting chamber, said latter chamber adapted to be connected to gas withdrawing means.
5. In a retort, the combination of, a vertical rectangular narrow distilling chamber, means for heating the two opposite sides thereof, the interior distilling chamber provided with a removable frame comprising opposite spaced sides each side supporting a series of vertically spaced horizontal shelves extending inward and sloping downward, with the shelves of one series arranged in staggered relation with those of the other, whereby to hold layers of the material being retorted and to feed the same from an upper shelf onto a lower, a gas-collecting chamber provided at one end of the distilling chamber, spaces under the said shelves constituting gas-collecting sheds and passageways which open into said gas-collecting chamber, said latter chamber adapted to be connected to gas withdrawing means.

MAGNUS RUDOLF KRAUL.
